C. E. CATHER.
METALLIC FASTENER FOR MERCHANDISE ENVELOPS.
APPLICATION FILED DEC. 6, 1915.

1,290,083.

Patented Jan. 7, 1919.

UNITED STATES PATENT OFFICE.

CHARLES E. CATHER, OF WORCESTER, MASSACHUSETTS, ASSIGNOR TO UNITED STATES ENVELOPE COMPANY, OF SPRINGFIELD, MASSACHUSETTS, A CORPORATION OF MAINE.

METALLIC FASTENER FOR MERCHANTISE-ENVELOPS.

1,290,083.

Specification of Letters Patent.

Patented Jan. 7, 1919.

Application filed December 6, 1915. Serial No. 65,248.

To all whom it may concern:

Be it known that I, CHARLES E. CATHER, a citizen of the United States, residing at Worcester, in the county of Worcester and 5 Commonwealth of Massachusetts, have invented a new and useful Improvement in Metallic Fasteners for Merchandise-Envelops, of which the following is a specification accompanied by drawings forming a 10 part of the same, in which the construction of my improved metallic fastener is illustrated, the novel features being described and specifically pointed out in the accompanying specification and appended claims.

15 Referring to the drawings,

Figure 1 is a front view of a metallic fastener embodying my invention, and attached to an envelop.

Fig. 2 is a perspective view of the seal 20 flap end of the envelop showing my improved metallic fastener in position to be inserted through the opening in the seal flap.

Fig. 3 represents a sectional view of a 25 merchandise envelop having my improved fastener attached thereto, with the bendable tongues thereof shown in the same position as in Fig. 2.

Similar reference characters refer to similar parts in the different figures.

30 In the accompanying drawings, 1 denotes the body portion of an envelop and 2 the seal flap, having an opening 3 to receive a pair of bendable tongues forming part of the metallic fastener, which is represented 35 in a flat or extended position in Fig. 1 and comprises a central plate 4 having projecting from opposite sides thereof the two bendable tongues 5 and 6. The plate 4 is attached to the body of the envelop in any 40 known manner, in the present instance by spurs 7 which pass through the body portion of the envelop and are clenched upon the inner side.

45 In securing the seal flap the two bendable tongues 5 and 6 are bent upwardly as shown in Figs. 2 and 3, thereby bringing the free ends of the tongues into proximity. The tongue 5 is considerably longer than the tongue 6, so that when the tongues are bent 50 up symmetrically from their junction with the central plate 4 the free end of the tongue 6 will contact with the side of the longer tongue 5 at a point 8 some distance below the free end of the tongue 6, the two tongues 55 forming with the central plate 4 an isosceles

triangle between the central plate 4 and the point 8. The extension 9 of the tongue 6 above the point 8 serves as a guide to conduct the seal flap over the tip of the tongue 5 and cause the opening 3 to be centered 60 around the base of the tongues. When the seal flap has been closed upon the body of the envelop the extension 9 also facilitates the bending of the tongue 6 down upon the body of the envelop, leaving the tongue 5 65 free to be subsequently bent down, thereby fastening the seal flap and closing the envelop.

The extension 9 of the longer tongue 5 70 I prefer to sharpen, while the end of the shorter tongue is cut square across. The shorter tongue, in the positions shown in Figs. 2 and 3, furnishes a support for the longer tongue, which presents a sharp tip 10 adapted to puncture the seal flap when the 75 opening 3 has been omitted. A metallic fastener having means for its ready attachment to the body portion of an envelop may be used with any ordinary commercial envelop, utilizing the sharp tip 10 for the purpose of puncturing the seal flap, and as soon as the latter has passed over the free end of the shorter tongue pressing both tongues together, while the seal flap is moved down 80 upon the body of the envelop.

85 I claim,

1. As an article of manufacture, a metallic fastener for envelops, comprising a base plate provided with means for its attachment to the body of an envelop, a pair of bendable tongues extending laterally from opposite sides of said plate and in the plane of the plate, with one of the tongues longer than the other and provided with a pointed tip, said tongues being spaced apart in the plane of the plate, so the tongues when bent toward each other at their junction with the base plate for insertion through the seal flap of the envelop will form with the base plate an isosceles triangle, with the pointed tip of the longer of said tongues extending across and beyond the tip of the shorter tongue.

2. The combination with an envelop provided with a seal flap, of a metal fastener comprising a base plate attached to the body of the envelop beneath said seal flap, and provided with a pair of bendable tongues extending laterally from the opposite sides of the base plate and in the plane thereof,

with one of said tongues pointed and longer than the other, whereby when said tongues are bent upwardly at their junction with the base plate to bring the tongues together, 5 said pointed tongue will project beyond the tip of the shorter tongue for insertion through the seal flap.

3. The combination with an envelop having a seal flap, of a metal fastener comprising 10 a base plate attached to the body of the envelop beneath said seal flap and provided with a pair of bendable tongues extending laterally from the opposite sides of the base plate and in the plane thereof, with 15 one of said tongues pointed and longer than

the other, and with the end of the shorter tongue square, whereby when said tongues are bent upwardly at their junction with the base plate to bring the tongues together, said shorter tongue will bear against the 20 longer tongue and the longer tongue will project beyond the tip of the shorter tongue for insertion through the seal flap, said tongues below their points of contact forming with the base plate an isosceles triangle. 25

Dated this 27th day of November 1915.

CHARLES E. CATHER.
